B. H. BLOCKSM.
COMBINED SLEEPING BAG AND MATTRESS.
APPLICATION FILED SEPT. 6, 1917.

1,284,046.

Patented Nov. 5, 1918.

UNITED STATES PATENT OFFICE.

BERGET H. BLOCKSOM, OF CHICAGO, ILLINOIS, ASSIGNOR TO WILSON & CO., INC., OF CHICAGO, ILLINOIS, A CORPORATION OF NEW YORK.

COMBINED SLEEPING-BAG AND MATTRESS.

1,284,046.

Specification of Letters Patent. Patented Nov. 5, 1918.

Application filed September 6, 1917. Serial No. 190,055.

To all whom it may concern:

Be it known that I, BERGET H. BLOCKSOM, a citizen of the United States, residing at Chicago, in the county of Cook and State 5 of Illinois, have invented certain new and useful Improvements in Combined Sleeping-Bags and Mattresses, of which the following is a specification.

The object of this invention is, primarily, 10 to provide a combined sleeping bag and mattress which is light in weight, simple in construction and compact in form and is especially adapted for use in the army and for camping purposes generally.

15 Another object is to provide a device of this character which will not only be comfortable and restful to the occupant but will fully protect him, when used in the open, against bad weather.

20 A further object is to provide a device of this character which can be used on a cot as well as on the ground, in the barracks and in the field, and which can be quickly rolled into a small bundle for transporting 25 and as easily opened up for use.

And a still further object is to construct the device so that it can be used as a receptacle for bed clothes and clothing which can be rolled up therein for transporting and 30 fully protected in a secure and compact roll.

In the accompanying drawing, illustrating the invention,

Figure 1 is a perspective view showing the main flap elevated at the head end of 35 the bag and also showing the flap opened up somewhat more than it would be in actual use perhaps, but for the purpose of more fully illustrating the structure;

Fig. 2 is a longitudinal section;

40 Fig. 3 is a transverse sectional view on the line 3—3 of Fig. 2, and

Fig. 4 illustrates the device when rolled and secured for transporting.

Fig. 5 is a detail perspective view showing one corner of the bag with the parts thereof distended and partly broken away.

Referring to the drawings the mattress comprises a filler 5 and a covering 6 and is made of sufficient width to accommodate 50 the average man and about six and one-half feet long. The filler is preferably hair but I may use any other suitable filler such as cotton, cotton felt or shoddy. The covering is preferably made of waterproof material

such as army duck, but any other suitable 55 material may be used.

In the construction which I now prefer the top 7 and bottom 8 of the mattress covering are joined in a suitable manner at their edges to provide a tight covering which 60 will snugly inclose the filler and preserve its shape and which will facilitate rolling the device into a handy bundle of small compass.

A pillow is provided at the head end of 65 the mattress and it comprises a filler 10 and a covering 11, preferably made of the same material as the mattress. The filler is laid upon the mattress covering and the pillow covering 11 is then sewed or otherwise 70 secured at its edges to the mattress covering.

The mattress forms the bottom of the bag which comprises a main or body flap consisting of the top 12, the side 13 fastened at 75 its edges to the mattress and the top, the side 14 fastened at one edge to the top and for a portion of its other edge to the side edge of the mattress, and the foot end 15 fastened at its edges to the mattress, the top 80 and the sides of the flap.

At the head end of the bag there is provided a hood for covering the head which consists of an end 16 fastened to the mattress and the side 13, and a flap 17 fastened 85 to the end 16 and also to the side 13 for a distance from the head end of the mattress and where said side is fastened to the top 12.

The construction of the main flap with 90 its sides and ends provides that desired fullness which is required to accommodate the occupant comfortably and enables the occupant to move and turn over without disturbing any of the parts of the bag. The lower end of the bag provides a pocket in 95 which extra blankets, clothing or other things may be conveniently stored, and they will be protected against the weather and against loss. This pocket also serves the purpose of confining the occupant's feet 100 against accidental exposure and at the same time prevents discomfort and allows freedom of movement. Tapes 18 or other suitable fastening means are provided for securing the free edge of the main flap to the 105 mattress.

The hood is provided to cover the head of the occupant as a protection against the

weather and also against insects and when not in use it can be thrown out of the way over the upper edge of the pillow.

The device is intended to be rolled upon itself into a roll for transporting and I provide tapes 20 to secure it in this form. These tapes are preferably secured to the mattress covering at the foot end thereof or in any other convenient position for tying, but they 10 may be used separate or other suitable means may be substituted therefor.

The invention provides a comfortable device of this character which can be easily and quickly made ready for use and which 15 is capable of being formed into a compact and secure roll for transporting. It will be readily appreciated that clothes, blankets and other things may be rolled up in the device for transporting and that they will 20 be fully protected against loss, dirt and the weather. The construction is such that the mattress and bag may be well aired and cleaned and yet there are no separate or detachable parts which might easily be lost. 25 The device may be used on the ground or on a floor or on a cot or even in a hammock, and when rolled for transporting it is in convenient form for handling.

The invention has a further important 30 advantage of being light in weight, it having been demonstrated that the device can be satisfactorily made, weighing about fourteen pounds, and since it can be easily rolled into a compact bundle for transporting and quickly prepared for instant use it has been 35 found to be especially adapted for army service.

It will be apparent that various changes

may be made in the form, construction and arrangement of the parts without departing 40 from the spirit and scope of the invention or sacrificing any of the material advantages thereof, the form hereinbefore described being merely a preferred embodiment thereof.

I claim:

1. A sleeping bag comprising a mattress forming the bottom of the bag, a body covering including a side fastened to the mattress, and a hood fastened to the head end of 50 the mattress and to the adjacent end of said side of the body covering and also to said side for a distance from the head end of the mattress and beneath said covering.

2. A sleeping bag comprising a mattress 55 forming the bottom of the bag, a pillow consisting of a filler laid upon the mattress and a covering for the pillow secured to the mattress, a body covering having a top, foot end and sides, one side and the foot end being fastened throughout their length to the mattress and the other side being fastened to the mattress adjacent the foot of the bag and detachably connected with the mattress 60 for the remainder of its length, and a hood consisting of an end fastened to the head of the mattress and to the fastened side of the body covering and a flap fastened to said end and also to said side where the side and top are secured together and arranged beneath the top and above the pillow.

BERGET H. BLOCKSOM.
